UNITED STATES PATENT OFFICE.

EVRAH C. LIPPS, OF DETROIT, MICHIGAN, ASSIGNOR TO PACKARD MOTOR CAR COMPANY, OF DETROIT, MICHIGAN, A CORPORATION OF MICHIGAN.

GRINDING APPARATUS.

Application filed March 15, 1924. Serial No. 699,418.

This invention relates to grinding apparatus and particularly to large high speed grinding wheels such as are used in the grinding of large surfaces. Such grinding 5 wheels are frequently manufactured of abrasive material, such as carborundum, in the shape of large hollow cylinders having an outside diameter as large as thirty inches and an internal bore of twenty-six inches or 10 more, the grinding being done on the annular face of the wheel. The hollow cylinders are usually supported in a driving hub to which they are clamped, or cemented, and are rotated through this hub in the ordinary 15 way.

Because of the dimensions of the wheel and the low mechanical strength of the material, such wheels are subjected to a high percentage of breakage, both in manufacture 20 and shipment, and in subsequent use. The breaking or cracking of such a wheel entails scrapping of the entire wheel, and as the cost of wheels of this type is quite high, the use thereof has frequently proved to be expensive. 25

One object of the invention is to provide a grinding wheel of the character designated in which breaks and cracks may be localized, and loss of the entire wheel upon the development of a minor injury may be prevented.

Other objects of the invention will appear from the following description taken in connection with the drawing, which forms 35 a part of this specification, and in which:

Fig. 1 is a plan view of a grinding wheel constructed in accordance with the invention;

Fig. 2 is a side view, partially in section, 40 of the grinding wheel shown in Fig. 1;

Fig. 3 is an enlarged fragmentary section, taken substantially on the line 3-3 of Fig. 1, and

Fig. 4 is a similar enlarged section, taken 45 substantially on the line 4-4 of Fig. 2.

Referring to the drawing, at 10 is shown a grinding wheel constructed in accordance with this invention, comprising segments 11, composed of carborundum or other suitable 50 abrasive material, arranged to form a hollow cylinder. Between the upper portions of the segments 11 are suitable separators 12, which may be formed of thin strips of any suitable non-abrasive material, such as 55 paper or cardboard. The separators 12 are

preferably cemented as at 13 to the radially disposed faces of the segments 11, and any suitable cement may be employed for this purpose. It has been found, however, that a silicious cement is well adapted for this 60 purpose, and that sodium silicate works particularly well.

The lower portion of the cylindrical wheel 10 is supported in a suitable driving hub 14, having a disk portion 16 on which the lower 65 annular face of the cylinder is adapted to rest, and having an axially disposed peripheral flange 17, adapted to embrace the lower portion of the segments composing the cylinder. This hub 14 is provided with 70 a suitable drive shaft 18, coaxial therewith and mounted in appropriate bearings (not shown), whereby the hub may be rotated in a manner well understood in the art to which this invention relates. 75

The spaces between the segments 11 below the separators 13, and between the outer face of the segments 11 and the inner face of the flange 17 may be filled with any suitable material 19 having a cementing effect 80 thereon. An appropriate material for this purpose is sulphur, which is preferably poured into the designated spaces while in a molten condition and is allowed to harden therein. 85

The upper portion of the cylinder 10 may be provided with one or more bands or hoop members 21, by means of which the segments 11 are pressed into peripheral engagement with the separators 12 and the whole cylinder 10 bound firmly together. The bands 21 may be set into positioning grooves, formed in circumferential alinement in the segments 11, but they are preferably clamped directly on the outer surface of the segments, and are 90 removed as the wheel wears down. The meeting ends of the bands are preferably provided with suitable tensioning means, such as the bolt 23 connecting the ears 24 formed on the band, by means of which 95 these bands may be contracted into close engagement with the segments 11.

It will be evident that this structure provides a grinding wheel in which cracks and breaks may be localized in one or more of 100 the segments, so that upon the development of such a minor defect it is not necessary to throw away the entire wheel. In the event of a break or a crack occurring in one of the segments 11, the hoops 21 are loosened, 110

the separators 12 adjacent the damaged section are removed in any suitable manner, as by sawing, the sulphur is softened as by heating, and the section taken out of the wheel. A new and undamaged section may be then inserted in place of the section removed, thus confining the loss to the cost of one of the sections.

It will be understood that various forms 10 of the invention other than those described above may be used without departing from the spirit or scope of the invention.

What is claimed is:

- 15 1. A cylindrical grinding wheel comprising segments of abrasive material, thin non-abrasive strips arranged between the segments, and a cement including silicate of soda to secure the strips between the segments.
- 20 2. A cylindrical grinding wheel comprising segments of abrasive material, thin non-abrasive strips cemented between the segments for a portion of the length of the cylinder, the remainder of the space between 25 the segments being filled with sulphur.
- 25 3. A cylindrical grinding wheel comprising

ing segments of abrasive material, strips arranged between the segments, a silicious cement between the strips and the segments for a portion of the length of the cylinder, 30 and a filler including sulphur in the remainder of the space between the segments.

4. A grinding wheel comprising segments of abrasive material arranged to form a hollow cylinder, a drive hub therefor having an 35 axially disposed flange adapted to embrace the lower ends of the segments, thin separators between the upper ends of the segments, hoops clamping the segments above the hub, and filling material for the space between 40 the segments and below the separators.

5. A grinding wheel comprising segments of abrasive material arranged to form a hollow cylinder, a drive hub adapted to embrace one end of the cylinder, paper separators cemented between the segments at the free end of the cylinder, and a sulphur filler 45 between the segments below the separators and between the separators and said hub.

In testimony whereof I affix my signature.

EVRAH C. LIPPS.
